SOLENOID VALVE

James K. Horne, Dover, N.H., assignor to Minneapolis-Honeywell Regulator Company, Minneapolis, Minn., a corporation of Delaware

Application December 24, 1956, Serial No. 630,357

4 Claims. (Cl. 251—130)

The invention relates to automatic-recycling and manually-operable means for power operated valves.

Valves of this general type are well known in the art and this invention relates specifically to an automatic recycling mechanism for power operated valves described in the copending application of John R. Jamieson, Serial No. 507,552, and filed May 11, 1955, although it is deemed to be obvious that the mechanism is capable of being used with valves having somewhat different construction than that of the Jamieson design.

One of the objects of this invention is to provide an inexpensive, reliable and compact automatic recycling mechanism for power operated valves in general and, more specifically, the valve disclosed in the above mentioned Jamieson application.

Another object of the invention is to provide an automatic recycling mechanism wherein a switch for bridging control contacts for the power means of a valve is located outside of a chamber housing the motor and is actuated by the same manually operable means for actuating the motor to its open position.

Other objects of the invention will become apparent upon reading the following detailed description of the invention in conjunction with the accompanying drawings wherein:

Figure 1 is a vertical sectional view of the valve along its longitudinal axis;

Figure 2 is a view of the inside of the cover of the valves;

Figure 3 is a cross sectional view of the valve taken along the line 3—3 of Figure 1, and

Figure 4 is a plan view of the valve with a portion of the terminal housing removed and a portion of the terminal block broken away.

The preferred embodiment of the invention consists of a valve body portion 11 having a threaded inlet 12 and a threaded outlet 13, with an apertured and inclined partition wall 14 therebetween. The inlet side of the wall 14 has a flat surface 15 that serves as a valve seat around the aperture 14a that is adapted to be opened and closed by a valve 16.

A housing 17 is secured to the body portion 11 by means of bolts (not shown) with a gasket 18 therebetween.

A solenoid 19 has a bracket 19a thereon that is secured to the housing 17 by means of bolts 20. The plunger (not shown) of the solenoid is connected to a yoke 21 that, in turn, is operably connected by a pair of pins 22 to a lever 23.

The lever 23 is pivoted in the housing 17 on a pivot 24 that extends through the lever with the ends of the pivot resting between two pairs of lugs 25 in the bottom of the housing 17. The pivot is held against the bottom of the housing and between the lugs by means of a Y-shaped leaf spring 26 that is clamped to the housing 17 by the bracket 19a and bolts 20. The lever 23 also has a pair of upwardly and outwardly extending arms 23a and 23b,

2

each of which has an elongated slot therein for reception of the pivot pins 22 on the solenoid yoke 21. The lever 23 has a projection 23c secured thereto with a diaphragm seal 27 clamped therebetween. The diaphragm is clamped around its periphery to the underside of the bottom of the housing 17 by means of a ring 28 held in position by a plurality of bolts 29 to seal an opening 30 in the bottom of the housing through which the lever extends. An arm 31 is held on the lower end of the extension 23c by the headed over end 23d of a pin extending from the lever 23 through the diaphragm 27, the extension 23c and the arm 31. The valve 16 is supported by the outer end of the arm 31 by having a stem portion 16a thereof extend through an opening in the arm 31 and retained thereon by means of a split ring 32. A helical spring 33 resiliently and swivelly mounts the valve 16 on the arm 31.

The arm 23a of the lever 23 has an extension 23e that is inclined upwardly and inwardly with respect to the solenoid and is adapted to be engaged by the laterally extending arm 34a of a lever 34 pivotally secured to a cover 35 for the housing 17 by means of a bolt 36 or by staking the end of a boss extension serving as the pivot for the lever. The housing 35 is secured to the housing 17 by means of bolts not shown with an O-ring seal therebetween. This lever has a slot 34b substantially parallel to the longitudinal axis of the lever 34 with a notch 34c extending transversely therefrom at the end of the slot nearest the pivot 36.

30 The lever 34 is adapted to be actuated to position the arm 34a against the arm 23e and to move the valve 16 to its open position by means of an externally positioned control knob 38. The knob 38 is fixed on the shaft 39 that extends through the top wall of the cover 35. The shaft 39 has an O-ring seal 40 between it and the cover 35 and carries at its inner end a crank arm 41. The outer end of the arm 41 carries a transversely extending pin 42 that extends through the slot 34b in the lever 34. It is thus seen that by rotation of the knob 38, the pin 42

40 will rotate the lever 34 which, in turn, will rotate the lever 23 to open the valve and to move the plunger to a position approaching its energized position. When in this position, the pin 42 will engage in the notch 34c and will be retained therein by the tendency of the lever 34 to move in the opposite direction under the bias of the solenoid spring 21a. While a coiled tension spring 43, anchored at one of its ends to a pin 44 on the cover 35 and at its other end to the crank arm 41, tends to move the crank arm 41 and the knob 38 to its starting position, 45 this force is not sufficiently great to kick the pin 42 out of the notch 34c against the bias of the spring 21a of the solenoid plunger. The crank arm 41 and pin 42 will retain the valve in its open position until either the solenoid is energized to pull the yoke 21 inwardly an additional 50 distance to relieve the force exerted by the spring 21a on the lever 34, so as to enable the spring 43 to kick the pin out of the notch 34c and return the knob and the crank arm to its inoperative or starting position, or by manually forcing the pin 42 out of the notch by manually turning the knob in its returning direction.

In order to provide for automatic returning of the valve to its closed position or to the control of a room thermostat which normally controls the energization of the solenoid, a switch in the form of a flexible contact arm 45 is secured at one of its ends to a terminal member 46 and is adapted to engage another terminal member 47 at its other end when the arm 45 is flexed against the terminal 47. A headed plunger 48 bears against an intermediate portion of the arm 45 and has the reduced diameter portion thereof extending through an aperture in a terminal block 49—50 for engagement with a cam member 51

moulded on the inner or bottom side of the knob 38. This cam-portion 51 has a bearing surface that is eccentric to the axis of the knob or shaft 39 so that when the knob is rotated to the valve "open" position, the contact arm 45 engages terminal 47.

The terminal block, consisting of the portions 49 and 50, are held together by means to terminal members 46 and 46a extending therethrough and through apertures in the housing 35 and through an insulation strip 52 on the inner side of the cover 35. A cover 53 has an opening 54 therein to permit leads extending from a heating system to enter for connection to the terminals 46, 47 and 46a. The cover 53 is adapted to be secured to the cover 35 by means of bolts (not shown). Terminal 46 is connected to one end of the solenoid coil and terminal 46a is connected to the other end.

In the connection of the terminals to a heating control system, it is deemed to be obvious that the terminal 46 will be connected by a lead line 55 to one side of a room thermostat 56 and that the terminal 47 will be connected by a lead 57 to the other side of a room thermostat. The terminal 46a is connected to one line of a source of power 58 by lead line 59 while the other side of the power source is connected to the thermostat and terminal 47 through a lead line 60.

Operation

The normal operation of the valve will be under the control of room thermostat 56 connected in series with the coil of the valve and a source of electrical current. However, in the event of power failure, it is possible to place the heating system in operation by manually rotating the knob 38 to its valve open position wherein it holds the valve open and simultaneously closes the switch arm 45 against the contact 47 to shunt out the room thermostat. The purpose of this shorting out of the room thermostat is to enable the valve to transfer to automatic operation upon power resumption, regardless of whether or not the room thermostat is calling for operation of the valve at the time power is resumed. As indicated previously, the manual operation of the valve by the knob does not fully move the plunger to its innermost position but only sufficiently far to open the valve for operation purposes and still enable the plunger to move in an additional distance upon the solenoid being energized, so as to release the pin 42 from the notch 34c in the lever that is holding the valve open. This is accomplished by releasing the tension on the pin 42 resulting from the tendency of the lever 34 to move in a counterclockwise direction, as shown in Figure 2, under the bias of the solenoid spring 21a. By relieving this tension, the spring 43 is sufficiently strong to cam the pin 42 out of the notch 34c and to permit the knob to be returned to its valve released position and the switch 45 to be biased under its own tension away from the contact 47.

While the preferred embodiment of the invention has been described above, it is deemed to be apparent to those skilled in the art how modifications may be made therein without departing from the spirit of the invention. Therefore, the scope of the invention should be determined from the appended claims.

I claim:

1. A control device comprising a member movable between first and second positions and normally biased to its second position, an electric motor means for actuating said member to its first position, a switch for said motor means normally biased to an "off" position but movable to an "on" position to supply power to said motor means, a lever pivoted at one of its ends on a fixed pivot and engaging said motor means at its other end, said lever having a bayonet slot intermediate its

ends, a manually operable knob having a shaft extending through a wall of said device, a crank on the inner end of said shaft and having a pin extending laterally therefrom and into said bayonet slot, and a cam having a surface eccentric to said shaft and positioned to actuate said switch to its "on" position when said knob is rotated to move said motor means nearly to its first position.

2. A control device comprising a member movable between first and second positions and normally biased to its second position, a motor means for actuating said member to its first position, control means for said motor means normally biased to an "off" position but movable to an "on" position to supply power to said motor means, a lever pivoted at one of its ends on a fixed pivot and engaging said motor means at its other end, said lever having a bayonet slot intermediate its ends, a manually operable knob having a shaft extending through a wall of said device, a crank on the inner end of said shaft and having a pin extending laterally therefrom and into said bayonet slot, and a cam having a surface eccentric to said shaft and positioned to actuate said control means to its "on" position when said knob is rotated to move said motor means nearly to its first position, said lever being capable of holding said member near its first position and the control means in its "on" position until released by energization of said motor means.

3. In a control device having a valve and a control member for actuating said valve between first and second positions and normally biased to its second position, the combination comprising a motor means for actuating said member to its "on" position and control means for said motor means normally biased to an "off" position but movable to an "on" position to supply power to said motor means; the combination comprising a lever pivoted at one of its ends on a fixed pivot and positioned to engage said motor means at its other end, said lever having a slot intermediate its ends, said slot having a notch therein, a manually operable knob having a shaft extending through a wall of said device, a crank on the inner end of said shaft and having a pin extending laterally therefrom and into said bayonet slot, and a cam having a surface eccentric to said shaft and positioned to actuate said control means to its "on" position when said knob is rotated to move said motor means nearly to its first position and to position the pin in the notch of the lever slot to retain said control means in its "on" position.

4. A control comprising a valve movable between "open" and "closed" positions and normally biased to its "closed" position, a motor means for actuating said valve to its "open" position, control means for said motor normally biased to an "off" position but movable to an "on" position to supply power to said motor means, a lever pivoted at one of its ends and engaging said motor means at its other end, said lever having a bayonet slot intermediate its ends, a manually operable knob having a shaft extending through a wall of said device, a crank on the inner end of said shaft and having a pin extending laterally therefrom and into said bayonet slot, and a cam having a surface eccentric to said shaft and positioned to actuate said control means to its "on" position when said knob is rotated to move said motor means nearly to its valve open position, said bayonet slot being capable of holding said valve in said position until energization of said motor means relieves the bias of said motor means on the pin through the bayonet slot.
